(57) **CLAIM**

The ornamental design for a camera lens, as shown and described.

DESCRIPTION

FIG. 1 is a perspective view of a camera lens, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged view of the encircled area 8 in FIG. 1; and,

FIG. 9 is an enlarged view of the encircled area 9 in FIG. 1. The broken lines depict portions of a camera lens in which the design is embodied that form no part of the claimed design.
